UNITED STATES PATENT OFFICE.

EDWARD S. SLOCUM, OF CHICAGO, ILLINOIS.

REFLECTOR.

1,120,750.

Specification of Letters Patent. Patented Dec. 15, 1914.

Application filed February 9, 1914. Serial No. 817,391.

To all whom it may concern:

Be it known that I, EDWARD S. SLOCUM, a citizen of the United States, residing at Chicago, in the county of Cook and State of Illinois, have invented a certain new and useful Improvement in Reflectors, of which the following is a specification.

My invention relates to indirect lighting fixtures, more particularly for electric lighting, and the object of the invention is to provide a reflector which will give uniform diffusion over a large surface of the ceiling against which the light is to be thrown.

I accomplish my object by the construction illustrated in the accompanying drawing, in which—

Figure 1 is an axial section of a fixture embodying my invention. Fig. 2 is a top plan view, and Fig. 3 is an axial section of the mirror.

Similar numerals refer to similar parts in the different views.

The reflecting portion of the fixture, shown separately in Fig. 3, consists of a shallow conical portion 1 having a spherical segmental portion 2 at the center. In the present design, the diameter of the segmental portion is about one-third the total diameter of the reflector. The top of the segmental portion rises to a point slightly beneath the plane of the upper rim of the conical portion, the center of curvature of the segmental portion being below the point where the apex of the conical portion would be located in case the side of the conical portion were produced. While the configuration may be slightly varied without exceeding the scope of the invention, the sides of the conical portion lie preferably at an angle of approximately fifteen degrees to the plane of the upper base of the cone, the reflector thus being shallow but affording space for the lamps 3 in the depression 4 formed at the junction of the spherical and conical portions.

The portions 1 and 2 are made, usually, of glass backed by mercury or other material whereby the upper surface becomes reflective. These portions, which constitute a reflecting mirror, are mounted upon and reinforced by a shell 5 of any suitable material and construction.

The lamps 3, above mentioned, are carried at the inner ends of arms 6, said arms being supported at their outer ends in such manner that the lamps are vertically ad-

justable. In the present design, the arms pass between lugs 7 arranged in pairs at the rim of the device. Clevises 8 engage said lugs on the outside, and the parts are held together by bolts 9 provided with wing nuts 10 whereby the parts may be tightened. By backing off one of the nuts the parts may be loosened and the lamp raised or lowered as desired, whereupon, by tightening the 65 nut, the lamp will be held fast in the position to which it is adjusted.

In operation, the lamps will normally be adjusted to a position similar to that shown in the drawings, the center of illumination 70 being below the level of the outer rim of the reflector so that all horizontal light rays will be reflected upward. Said center of illumination, however, will be in or near the depression formed at the junction of the 75 conical and spherical portions of the reflector and preferably at or below the level of the top of the spherical portion. In consequence, the light rays or luminants will all be reflected in upward direction and will be 80 diffused over a large area of the ceiling above.

At the right end of Fig. 3 I have illustrated two extreme luminants at A and D. Intermediate luminants such as B and C 85 will be thrown more directly toward the ceiling. The field, however, will be large and of substantially uniform intensity, the size of the field depending upon the elevation to which the lamps are adjusted. 90

Having thus described my invention, what I claim as new and desire to secure by Letters Patent, is:

1. In a fixture for indirect electric lighting, a reflector comprising a conical portion, the concave side whereof is reflective, and a substantially spherical segmental portion concentric therewith, the segmental portion being reflective on its convex surface, the segmental portion having a diameter approximately one third of the total diameter of the reflector and the top of the segment rising to a point slightly below the plane of the top of the reflector. 95

2. In a fixture for indirect lighting, a 105 reflector comprising a shallow, right truncated cone having parallel bases, a spherical segmental portion, the base whereof is coincident with the smaller base of the conical portion, the top of the spherical portion 110 rising to a point near the larger base of the conical portion, the concave surface of

the conical portion and the convex surface of the segmental portion being reflective, and electric lamps having their illuminative centers located in the annular depression formed at the juncture of the conical and segmental portions.

3. In a fixture for indirect lighting, the combination of a reflector comprising a shallow, right truncated cone having parallel bases, a spherical segmental portion the base whereof is coincident with the smaller base of the conical portion, the base of the segmental portion being approximately one third of the external diameter of the conical portion, the center of curvature of the segmental portion being beneath the apex of the conical portion if the sides of the latter were produced, the top of the spherical portion rising to a point near the larger base of the conical portion, the concave surface of the conical portion and the convex surface of the segmental portion being reflective, electric lamp bulbs, and means supported at the periphery of the reflector for holding said lamp bulbs beneath the larger base of the conical portion and with their

centers approximately in the depression formed at the junction of the conical and segmental portions.

4. In a fixture for indirect lighting, the combination of a reflector having a spherical portion at the center and a conical portion surrounding said spherical portion, the top of the spherical portion being slightly lower than the outer rim of the reflector, there being an annular depression at the junction of the spherical and conical portions of the reflector, electric lamp bulbs located at said depression, arms supporting said bulbs, and supporting means at the periphery of the reflector for supporting said arms, said supporting means being adjustable, whereby the lamps may be raised or lowered.

In witness whereof, I have hereunto subscribed my name in the presence of two witnesses.

EDWARD S. SLOCUM.
